UNITED STATES PATENT OFFICE.

SHERWOOD HINDS, OF CHICAGO, ILLINOIS, ASSIGNOR TO S. F. BOWSER & COMPANY, INC., OF FORT WAYNE, INDIANA, A CORPORATION OF INDIANA.

PUMP-DRIVE MECHANISM.

Application filed February 26, 1921. Serial No. 448,227.

To all whom it may concern:

Be it known that I, SHERWOOD HINDS, a citizen of the United States, residing at Chicago, in the county of Cook and State 5 of Illinois, have invented certain new and useful Improvements in Pump-Drive Mechanisms, of which the following is a specification.

My invention relates to driving mechanism for pumps, and the like, and has for 10 one of its objects the provision of a simple and efficient dispensing pump mechanism adaptable for being driven either by power or by hand.

15 A further object is the provision of a simple and efficient hand drive mechanism which can be easily and quickly attached or detached from a pump mechanism, or the like.

20 A still further object is the provision of a detachable hand drive mechanism adapted to operate a pump at slower speed on its working stroke than on its return stroke.

Other objects will appear hereinafter.

25 An embodiment of my invention is illustrated in the accompanying drawings, forming a part of this specification, and in which—

Fig. 1 is a longitudinal section taken 30 through a pump driving mechanism embodying my invention;

Fig. 2 is a section taken on line 2—2 of Fig. 1;

Fig. 3 is a view in perspective of a dog 35 used in the construction;

Fig. 4 is a section taken on line 4—4 of Fig. 1;

Fig. 5 is a section taken on line 5—5 of Fig. 1; and

40 Fig. 6 is a vertical section of power mechanism interchangeable with the hand power device in Fig. 1.

In ordering dispensing pumps for gasoline, lubricating oil, and the like, persons 45 often get such dispensing apparatus with hand power driving mechanism and then after using the same for a while want to apply power to such dispensing apparatus. It is the purpose of this invention to so 50 form the driving shaft of such dispensing apparatus so that it may be provided either with hand driving mechanism or power driving mechanism.

55 Referring more particularly to the drawings, I have indicated the fragments of a

pump housing 4 with an opening 5 therein, and on the housing 4 is provided a casing 6 having a flange with openings 7 which may be secured to the pump housing 4 in any desired manner. Axially of the casing 6 are bearings 8 and 9, and in the bearings 8 is journaled a shaft 10 having a cup-shaped enlargement 11 at one end thereof. At the other end of said shaft 10 is a restricted portion 12 on which is secured a 65 manually operable crank 13.

The operating shaft 14 of a dispensing pump is shown extending axially into casing 6 with a restricted portion 15 journaled in a bore 16 in the center of shaft 10. 70 A plate 18 has an opening in which the shaft 14 is disposed and it may also provide a bearing for said shaft. On the plate 18 is a casting 19 having studs 20 and 21 thereon. On the stud 20 is a gear 22 meshing with a gear 23, and the latter is journaled on stud 21. Gear 23 meshes with an internal gear 24 which has one end journaled in bearings 9 and the other end provided with a hub 25 journaled on cup member 11. Gear 22 meshes with teeth 17 cut in shaft 14, as clearly indicated in Fig. 5. The members 19 and 18 may be secured to a portion of housing 4 of the pump in any desirable manner, such as by screws 26. 85

The hub 25 of gear 24 has a cylindrical bore 27 concentric with shaft 14, and in said bore is mounted a friction ring 28. Said ring has a plurality of solid lugs 29 engaging bore 27 and one or more spring-pressed lugs 30 also engaging said bore. I have indicated two lugs 29 and one lug 30, but the number may be varied as desired. The lug 30 is mounted in a suitable opening in ring 28 and has a spring 31 pressing it 90 outwardly. Ring 28 is held against a shoulder 32 of hub 25 by a plate 33, and the latter secured to said hub by screws 34, or their equivalent. In the end of cup 11 is formed a diagonal cut or slot 35 in which is slidably mounted a dog 36. Said dog has an arm 37 disposed in a recess 28' in said ring 28 and a toe portion 38 on said arm engaging a notch 39 in said ring. Notch 39 and recess 28' are sufficiently large to permit easy movement of parts 37 and 38 in all movements of the dog 36. 95

Shaft 14 has a member rigidly associated therewith with a notch 40 in said member inside of the cup 11. In the present in- 100 105 110

stance the notch 40 is formed in a sleeve 41 connected to the shaft 14 by splines 42. (See Figs. 2 and 4). Said collar may be formed integral or attached in any other desirable manner. Opening into the bore of hub 25 is a notch 43 with one side cut away as at 43' in Fig. 2.

The casing 6 is preferably larger than the parts housed therein with a space 44 around said parts for the distribution of oil. A part 45 of this space extends up around shaft 10 in part 46 so that oil may be carried to all of the movable parts in said casing. An oil filling plug is indicated at the top of casing 6 in Fig. 1, and a drain plug is indicated near the bottom of said figure. The parts beforementioned are for driving the dispensing pump by hand.

In Fig. 6 I have indicated a power driven apparatus having a casing 6' attached to housing 4 of the pump casing. The casing 6' is formed so as to fit in housing 4 the same as casing 6 so that the power apparatus may be used or hand apparatus, as desired. Axially of casing 6' is indicated the driving shaft 14 of the pumping mechanism in substantially the same relation as the shaft occupies in Fig. 1 with respect to casing 6.

30 The power driving mechanism indicated in Fig. 6 may be any form of power driving mechanism desired, and that indicated is substantially the same as in my co-pending application, Serial No. 381,868, filed May 35 17, 1920, for fluid pressure motors. Said Fig. 6 of the present application is substantially the same as Fig. 10 in the application above referred to, with the exception of the change in shaft 31 of said application to 40 fit shaft 14 in the present application.

In the present application a shaft 49 has splines 50 thereon registering with splines 42 of shaft 14 with the collar 41 connecting said shaft 14 with shaft 49. The shaft 49 is indicated as mounted in bearings 51 in casing 6' with gear teeth 52 formed thereon meshing with a rack bar 53 which may be driven as set forth in my co-pending application, Serial No. 381,868.

50 In operation, when the device is fitted with the hand drive mechanism, the crank 13 is turned in one direction and this rotates shaft 10 with its cup 11, thereby moving dog 36 around collar 41 and in hub 25. The friction ring 28 being connected to the dog by toe 38 and arm 37 causes dog 36 to be slid into notch 40 of collar 41 when the crank is turned in a clockwise direction. This provides a direct connection between 60 shafts 10 and 14, thereby causing pump shaft 14 to be driven at the speed the crank is rotated. Upon rotating the crank 13 in a counter-clockwise direction, dog 36 is drawn by friction ring 28 outwardly into engagement with notch 43 which locks the hub 25

to cup member 11. Since the dog is moved from notch 40, the gear 24 rotates with crank 13, and through the connecting gears 22 and 23 and gear teeth 17, pump shaft 14 is driven at a faster speed than crank 13. 70 With this construction the pump shaft 14 is driven on its operating stroke at the rate of speed of crank 13, and upon the return stroke at a faster rate than crank 13.

When the power driven apparatus is connected to pump shaft 14, said shaft is operated in the manner set forth in my above-mentioned co-pending application.

By taking out the securing means from openings 7 of the flange of casing 6 the hand power device may all be slipped out of opening 5, with the exception of members 18 to 26, inclusive. The power driven apparatus may then be placed in position and locked therein with the same securing means as used to hold the hand power mechanism in place and be ready for operation at once. It will therefore be seen that either of the driving devices may be replaced with the other in a very simple and easy manner.

I claim:

1. The combination with a dispensing pump mechanism having an opening therein and a pump shaft in the casing with one end of said shaft adjacent said opening, of a gear housing detachably secured to the pump casing over said opening; and driving gearing mounted in the gear housing and connected with the shaft, said driving gearing being adapted for automatic disconnection from said shaft upon removal of the gear housing from the pump casing.

2. The combination with a casing for a dispensing pump and pump shaft mounted therein, of hand operated actuating mechanism for said shaft detachably secured to said pump casing in operative relation with said shaft and removable therefrom to expose said shaft in position to receive other forms of actuating mechanism.

3. The combination with a casing for a dispensing pump, of a pump shaft mounted therein; gearing for operating said shaft at different speeds in opposite directions; a hand crank for actuating said gearing; and a gear casing detachably secured to said pump casing and removably securing said gearing in operative relation with said pump shaft, so that removal of said gear casing and gearing will free said pump shaft for attachment to a power driving mechanism.

4. The combination with a dispensing pump casing and pump shaft mounted therein; of a gear casing attached to the pump casing; gearing in the gear casing; and a crank connected with the gearing, said gear casing, gearing and crank being removable as a unit from the pump casing and pump shaft.

5. The combination with a dispensing

- 5 pump casing having an opening therein and a pump shaft mounted centrally of said opening in said casing; of a gear casing fitting in said opening and secured to said 10 pump casing; gearing in said gear casing; a hand crank attached to said gearing; a collar splined on said shaft and attached to said gearing; a gear casing adapted for attachment to said pump casing and having a portion for extending into said opening; and a power driven shaft in the last-mentioned gear casing, said last-mentioned gear casing and shaft mounted therein being adapted to replace the first-mentioned gear casing, 15 gear and hand crank.
- 6 6. Pump gearing comprising a driving shaft; a pump shaft extending into the driving shaft; a gear journaled on the driving shaft and connected with the pump shaft; 20 and a clutch dog mounted in the driving shaft and adapted to engage the pump shaft when the driving shaft rotates in one direction and engage the gear when the driving shaft is rotated in the other direction.
- 7 7. Pump gearing comprising a casing; a pump shaft extending into said casing; a driving shaft alining with said pump shaft and having a portion telescoping over said pump shaft; a gear journaled on said driving shaft and in said casing; a connection between said gears and said pump shaft; a clutch dog adapted for sliding movement; and a friction member engaging said gear and connected with the dog for automatically shifting the latter.
- 8 8. Pump gearing comprising a casing; a pump shaft extending into said casing; a driving shaft extending into said casing; a direct drive connection between said driving shaft and pump shaft; a multiplying connection connecting said driving shaft with said pump shaft; and means for throwing said connections into operation, one at a time.
- 9 9. Pump gearing comprising a pump shaft; a driving shaft substantially alining with said pump shaft; a cup on said driving shaft extending onto said pump shaft; a gear having a hub journaled on said cup; a connection between said gear and said pump shaft; a dog slidably mounted in said cup; and means for moving said dog into operative engagement with said gear and said pump shaft, one at a time.
- 10 10. Pump gearing comprising a driving shaft; a driven shaft substantially alining with said driving shaft; a cup on the driving shaft extending over and journaled on said driven shaft; a gear hub journaled on said 15 cup; a friction ring extending around said driven shaft and frictionally locked to said hub; a connection between said gear and said driven shaft; and a dog slidably mounted in said cup and having a portion engaging said friction ring.
- 11 11. Pump gearing comprising a driven shaft having a notch therein; a driving shaft; a cup on said driving shaft having a slot therein adapted to be brought into registration with the notch in said driven shaft; a gear hub journaled on said cup and having a notch therein adapted to be brought into registration with the slot in said cup; a member frictionally locked in said gear hub having a notch therein; and a dog slidably mounted in the slot in said cup and having a portion engaging the notch in said frictionally locked member.
- 12 12. Pump gearing comprising a casing having two alining bearings therein; a driving shaft journaled in said bearings and having an opening at its center; a driven shaft having a restricted portion journaled in the opening in said driving shaft; a train of gears connected with the driven shaft; and a clutch member adapted to be alternately moved to connect the driving shaft directly with the driven shaft and also to be moved to connect the driving shaft with said gearing.
- 13 13. Pump gearing comprising alining driving and driven shafts; a direct connection between said shafts; a multiplying connection between said shafts comprising a gear surrounding both of said shafts; a housing extending around said gear and spaced therefrom providing an oil chamber; and means for throwing said connections into operation, one at a time.
- 14 14. Pump gearing comprising alining driving and driven shafts, a portion of the driving shaft extending around onto said driven shaft; a gearing connected with said driven shaft and having its hub journaled on said driving shaft, there being a shoulder adjacent the end of said driving shaft; a friction ring in said hub adjacent said shoulder; and a plate secured to said hub and holding said friction ring against said shoulder.
- 15 15. Pump gearing comprising a casing having an opening at one end; a plate closing said opening; a pump shaft extending through said plate into said casing; a driving shaft in alinement with the pump shaft; a cup portion on the driving shaft journaled on said pump shaft; a gear hub journaled on said cup and having one end engaging the casing and its other end engaging said plate; a connection between said gear and said pump shaft; a clutch member; and yieldable means adapted to move the clutch to directly connect said shafts when the driving shaft is turned in one direction and adapted to move the clutch to connect the driving shaft with said gear when the driving shaft is moved in the other direction.
- 16 16. Driving mechanism for a dispensing pump having a casing and a rotary shaft therein comprising a housing; a rotary mem-

ber journaled in said housing; a hand crank secured to said rotary member; and means for detachably securing said housing to said pump casing with said rotary member in driving relation with said shaft.

17. Driving mechanism for a dispensing pump having a casing and a rotary shaft journaled therein, said driving mechanism comprising a housing; a rotary member journaled in said housing; a hand crank for actuating said rotary member; means actuated by said rotary member for rotating said shaft in unison with said hand crank when said hand crank is turned in one direction; and gearing for driving said shaft at a different rate of speed from said hand crank when said hand crank is turned in an opposite direction, said housing, hand crank and rotary member being detachably secured 20 to said pump casing to hold said rotary member, gearing and shaft in operative relation with one another and being removable

therefrom to permit removal of said rotary member and substitution of power operating means for driving said shaft.

18. The combination with a dispensing pump casing having an opening therein and a pump shaft in said casing with one end having a roughened surface and disposed adjacent said opening, of a gear housing detachably secured to said pump casing over said opening, and driving gearing mounted in said gear housing and having a hollow portion slidably fitting the roughened end of said shaft for effecting operative connection between said gearing and shaft, said hollow portion of the gearing being slideable onto said shaft upon the gear housing being attached to said pump casing.

In testimony whereof I have signed my name to this specification on this 23d day of Feb., A. D. 1921.

SHERWOOD HINDS.
